UNITED STATES PATENT OFFICE

BENJAMIN RICHARDS, OF KENILWORTH, ILLINOIS, ASSIGNOR, BY MESNE ASSIGNMENTS, TO AMERICAN LA FRANCE AND FOAMITE CORPORATION, A CORPORATION OF NEW YORK

AUTOMATIC FIRE-PROTECTION DEVICE

Application filed November 12, 1921. Serial No. 514,482.

This invention relates to improvements in automatic fire protection devices. More particularly it relates to automatic sprinkler or quasi-sprinkler systems in which a device, which may preferably be an ordinary automatic sprinkler of any of the types now in common use, serves as a release for any desired agent external to the piping of the system and also, if desired, separately or jointly as a release for fluid in the piping system in the well known way. In thus serving, its force is imposed as a compressive force directly on the fusible element of the sprinkler, rather than by tension; and this is in addition to and without interference with the ordinary uses of a sprinkler.

The release for the external agent is accomplished without the need of liquid or gaseous pressure in the fluid distributing system; but the agent thus released by external means may be either outside or inside of, i. e. operating through, the distributing system. And, if the latter, it may be either a single liquid as water, or may be the result of combining liquids, as foam, or soda and acid, at a main control valve. As contrasted with present systems, all of which known to me require air or water, or something, under pressure in the distributing pipes, this needs nothing therein, yet the sprinkler serves as the releasing device. This makes possible a considerable saving, sufficient to make the advantages of automatic protection available in many places where the expense of present systems with air compressor and dry pipe valve is prohibitive. Compared with this last, apparatus of the invention may be equipped with a valve of simple and inexpensive type. However, if preferred, the invention can be used with a distributing system normally filled with fluid under pressure, such as water, air, carbon-dioxide, or other liquid or gas.

Circumstances under which the invention is particularly useful are, where air cannot be kept in a system, on account of the atmosphere having a corrosive action on steel and iron pipe, as in dye houses, tanneries, chemical works; or where the cost is a matter of importance; or where more prompt action is

wanted than is obtained by using an ordinary dry pipe system; or where it is desired for safety to prevent the discharge of a large volume of air upon the fire; or where the agent to be discharged is a gas, acid or other agent not desired continually in the pipes to avoid corrosion or danger to life.

To obtain the foregoing advantages the invention makes use of any ordinary or suitable type of sprinkler and combines with it a solid element tending to thrust the sprinkler open and operatively connected with the device which is to be released, be it dry valve, fire door, alarm, or what not without necessarily interfering with the normal office of the sprinkler. Preferably this solid opening element acts upon the sprinkler from within, as does the fluid medium which thrusts the sprinkler open in ordinary air and water systems, upon the dissolution of the strut thereof. The opening element may be wholly contained within the enclosure, but otherwise projects out of it to a latch or the like which is released by its movement, and is connected to the mechanism which is to be actuated. The impelling force for the actuation is here represented as being in a part and primarily a weight or spring, which is held back by the sprinkler. Suitable means may be provided to transmit impulse from the force released by the latch to the apparatus which is to be operated, in order either to operate it or to release some other force which is ready to operate it. For this various mediums may be employed, for example, a mechanical system of rods, ties and levers; or an electrical system or a compressed air system of such small capacity that it can be kept tight with a small hand pump, without need of the power compressor which is objectionably expensive as above mentioned and this tube, being so small, can be made of copper or brass without great expense.

The description which follows and the accompanying drawing illustrate embodiments of the invention. If used to operate a sprinkler system the water which is turned on practically instantaneously by the impulse transmitted upon the opening of the sprinkler rushes through the distribution system, un-

retarded by the presence and back pressure of any body of air, till it finds the open sprinkler, and is discharged therefrom, but not from others unless or until the fire opens them, at which time their supply is ready for them. The embodiments and arrangements here shown are to be taken as illustrative only, the invention being applicable in many other ways. It is intended that the patent shall 10 cover by suitable expression in the appended claims whatever features of patentable novelty exist in the invention disclosed.

In the accompanying drawings:

Figure 1 is a side elevation, in diagram, of apparatus, partly in section, arranged for use with a fluid or gas to be discharged by the sprinkler;

Figure 2 is a side elevation of a part of the same apparatus modified as it may be when 20 there is no fluid to be discharged;

Figures 3 and 4 are side elevations of two modifications, showing fragments corresponding to parts of Figure 1; and

Figure 5 is a similar elevation of a fragment of a modification of the type illustrated 25 in Figure 2.

Figure 6 is a horizontal section through a detail of Figure 3.

Referring to the drawings, 10, 10 indicate distribution piping of a sprinkler system which may be assumed to contain water as in an ordinary wet pipe system, or air under pressure as in an ordinary dry pipe system, or may contain other fire protective fluid, or may contain gas or air at atmospheric or other pressure or a vacuum. The reference numeral 11 designates a union fitting set into such a system of piping and having a socket 12 with screw threads adapted to receive the base 13 of a sprinkler, which for purposes of the invention may be of any ordinary or suitable type, acting by collapse of the strut 14 when a predetermined temperature has been attained. The discharge 40 orifice is represented as closed by a movable valve body 15, whose opening is prevented by the yoke 17, at whose head is the water distributing portion 16, mounted on the frame restraining the strut 14.

50 A feature of particular importance in the invention, comprising an internal strut is represented, in Figure 1, as a rod 18 pressing outward on the valve 15 and tending to open it, as pressure of air or water does in the sprinkler system now commonly in use. The rod 18 is guided by spiders 19 19' which center it in the nozzle. The rod may be of any suitable cross section, as for example triangular, passing through a round hole in the spider, 60 in which case the friction is reduced to a minimum; and it may extend inward from the sprinkler valve to any suitable distance, its function being to engage, in some suitable place and manner, an element whose release 65 will permit operation of the fire protective

apparatus. In Figure 1 this element is a keeper 20, which in full line position restrains movement of a lever 21 which is pulled by a weight 22. To illustrate various uses, this lever is shown equipped to operate sundry

protective devices whenever it is free to swing to its dotted line position. Thus, there is a cable 23 by which it can operate a latch 24

for releasing a self-closing fire door 25. There is another cable 33 having a lug 33' by which it can operate a latch 34 to release

a protective cover 35 for a vat which may be supposed to contain chemicals of some sort requiring that form of protection. There is another cable 43 extending through suitable

connection to raise a keeper 44 and thus to release a dry pipe valve 45. In the latter

case it may be assumed that water or an extinguishing gas under pressure stands in the pipe 46 and is, by the opening of the valve

45, admitted to the main riser 10^a which may be part of the distribution system 10 leading to the sprinkler which has operated the

valve. In this case the valve is illustrated as being held closed by a strut 47 whose length

can be adjusted by the turn buckle arrangement 48 for accurate setting, and which is based on a bridge 49 of which the keeper 44

constitutes one abutment. Upon the movement of the keeper the bridge 49 yields, al-

lowing water in pipe 46 to open the valve 45 and to rush through the distribution system to the sprinkler whose heat-responsive strut

14 has collapsed. As there is not back pres-

sure of air in the pipes, this flow is more

rapid than in ordinary dry pipe systems as

hitherto known, and avoids blowing the fire

by the discharge of the excess air. Prefer-

ably the pipes between the sprinkler and the

valve are filled with a gas which will not sup-

port combustion, further avoiding the evil

effect of air as formerly used.

The lever 21 is also represented as actuating a push pin 53 which by connecting the electrical contacts 54 sends out an impulse

through wires 55. This may operate electri-

cally any of the apparatus whose release or

actuation by mechanical means is herein de-

scribed, including an alarm, or, such an alarm

may be operated mechanically. And, as in-

dicated by the lever 21, and pin 53, considered

as a switch, mechanically operated, a pre-

determined movement of a part of the me-

chanical system may set an electrical system

into operation.

The illustrations thus given indicate the

variety of fire protective apparatus that may

be set into action instantly by the collapse of

the sprinkler strut 14. It is obvious that any

of them may be used without the others.

Figure 2 calls attention to a particular fea-

ture in which the water pipes 10 are replaced

by screw plugs 10'. In this case there is no

provision for water to reach the union fitting

11, and we have an illustration of an auto-

matic system, which may be called a quasi-sprinkler system, comprising an instance in which an ordinary sprinkler head serves as an automatic release for any desired fire apparatus. The simplicity of this device, as contrasted with the complications of automatic release apparatus heretofore known, together with the ease and convenience of resetting by taking an ordinary sprinkler out of the stock which a modern protected plant always has in abundance in reserve, will be manifest to those who are familiar with the more complicated releasing arrangements now on the market. In particular, the superiority to fusible link systems will be noted, because the heavy load that can be put on a sprinkler hastens the yielding when operating temperature has been reached. Obviously, the unfed sprinkler can release and permit the working of any additional apparatus desired, including an electrical circuit as indicated in Figure 1. In case it opens a main valve 45 as there indicated, the riser 10^a may be connected to open sprinklers arranged on a deluge system.

Assuming, however, that the collapse of the sprinkler strut 14 is desired to cause discharge of water from that very sprinkler the drawing shows in Figure 1 an arrangement by which the apparatus becomes tight for the discharge of all water through the sprinkler. To this end a case 60 is provided to hold the inward end of the rod 18 which extends so far inward from the valve 15 that it sticks out on the other side of the piping system, and to hold the keeper 20 which it restrains, this being connected with the union fitting 11 by a neck 61 screwed into it on the side opposite the sprinkler, having a small passage 62 through which the rod 18 runs loosely. The whole being arranged with the rod 18 vertical and with the sprinkler at the top, collapse of the strut, when heated, permits the rod 18 to rise, impelled by its load represented by the weight 22, or an equivalent spring, until the end of lever 21 has cleared the keeper 20 as indicated in the upper dotted line; whereupon the keeper 20 falls to the lower dotted line position, and with it the rod 18 carrying down a petticoat valve 63 to close the opening 62, at the top of which a valve seat may be provided as indicated. A guard 64 may be inserted higher up in the neck 61 to prevent the rod 18 from being thrown out of the apparatus on this upward movement. Water released at the main valve 45, rushing through the system and arriving at this sprinkler, is then discharged in the usual way; and there is no leakage through the opening provided for the rod 18 because the valve 63 thereon closes that opening. The rod, dropping down out of the passage does not interfere with the normal discharge of the sprinkler.

The connection from the rod 18 to the ap-

paratus that is to be operated may be effected by any suitable means, such, for example, as a system of ties or linkage of any sort, one of which is indicated in Figure 1, or an electrical system also indicated in Figure 1, where the wires 55 may operate a valve or automatic release, as well as the alarm above mentioned; or a pneumatic or other fluid system indicated in Figures 3 and 5. The type suggested in Figure 3 shows a fragment of an auxiliary air system of which the small chamber 71 and small pipe 73 are parts. The chamber is closed by a diaphragm 70 having a central perforation into which fits the valve-like head 78 of a rod 18' which corresponds in many respects to the rod 18. Pressure of air or other fluid such as acid which it might be desired to combine or add to a liquid already in the main pipes in the little copper pipe 73 and chamber 71 seats the diaphragm 70 against the valve head 78, and pushes outward on the rod 18' and sprinkler valve 15 so long as the strut 14 thereof remains intact. But upon the dissolution of the strut the rod 18' is free to rise and its head 78 thus releases air from

the system 71, 73. The nature and extent of this system is not shown, but it may be supposed to be arranged, according to principles well known, for controlling the action of a distant valve or other apparatus by reduction of air pressure on a pneumatic tripping device or piston. In this case, however, the capacity of the system would be relatively small; and therefore a proper pressure could be maintained under service conditions with simple and inexpensive apparatus. The rod 18', in the arrangement of Figure 3, is in two separable parts, the upper of which is a part of the rod for the strut purpose thus far mentioned, but is petticoated as at 79 so that the rush of water will carry it out, if it has not been sooner ejected; and one of the petticoats has an apron arranged unsymmetrically as at 79' so that it will be deflected when ejected and thus will pass clear of the water distributor 16 and not remain to clog the passage. This part of the rod is also designed with guides 79'' to maintain its alignment with rod 18.

Figure 5 illustrates apparatus similar to that of Figure 3 except that the small air connecting pipe 73' is concealed within the distribution pipe 10. In the arrangement shown in Figure 4, apparatus is illustrated for transmitting the operating impulse mechanically, and providing the self clearing nozzle of Figure 3. In this case, however, there may be water or air standing under pressure in the distribution system 10, the escape of which through the releasing device 125 will be prevented by the closure of valve 63', carried on the rod 18'', down upon a valve seat 62' arranged at the extremity of the neck 61 where it projects into the distribution system. Pressure of air or water in the

distribution pipes 10 will at all times tend to keep this valve 63' seated, and prevent leakage. While standing ready, the pressure upward on the rod 18", coming from the keeper 20, should be great enough to overcome the fluid pressure, but the valve is kept closed by pressure from the sprinkler valve 15, effected by screwing the sprinkler in; when this disappears, as when the sprinkler strut 14 has collapsed, the valve 63' will open, permitting the rod to function and then return to position to prevent leakage. In order to make the valve 63' automatically seated notwithstanding the varying degrees 10 the sprinkler may be screwed into the fitting, a compression spring 63" may be provided, strung around the rod 18 and allowing some variation of distance between the sprinkler head and the seat of the valve 63', one method 15 of doing which is indicated in Figure 4. Apparatus of this type may be used to operate nearby protective devices through the cord 33, or as heretofore described, in addition to sprinkling the fire. The main control of the 20 distant supply or dry pipe valve may be by some other system; for example, by the usual method of an automatic dry pipe valve controlled by the pressure of air in the pipe 10^a, assumed for this purpose to be connected to 25 the pipes 10.

In some cases it may be found that there is a sufficient pressure in the system so that the valve 63' can be kept seated by air pressure alone, yet sufficient drop consequent 30 upon the opening of the sprinkler so that it will surely be opened by the pre-existing upward pressure of the keeper 20, when the opening of the sprinkler has occurred.

In these cases of the separable rod, part 40 may be ejected and part may drop, out of the way of the current of water. Although Figure 1 indicates a direct connection from the weight 22, associated with a sprinkler, to the distant dry pipe valve or to other apparatus, it will often be inconvenient to have at each sprinkler a weight heavy enough to do the required work at the distance, and such weight is unnecessary. The weight 22 or an equivalent spring may be small, at each 45 sprinkler head, and a number of them may be connected to the same wire 23, 33 or 43 which may run to a relay weight (not shown) which is tripped by movement of the cable 23, 33 or 43, and whose tripping relays the 50 pull in sufficient strength to the particular apparatus that is to be operated, or the load may be put directly in the release levers without weight.

I claim as my invention:

60 1. The combination with a sprinkler head structure having a thermally responsive closure, of a strut pressing outward on said closure said strut comprising a plurality of separable parts, one of which parts is adapted to be carried out upon the opening of

said closure and the whole of which parts are adapted in combination to form part of a connection with a second fire protective device and to restrain the operation thereof until the said opening of the closure releases 70 it.

2. The combination, with a sprinkler head having a thermally responsive closure, of a strut pressing outward on said closure; said strut having a deflecting vane whereby it is 75 adapted to be ejected through the opening of said closure, and adapted to restrain the operation of a fire protective device before being released by said closure.

3. The combination, with a sprinkler head 80 having a thermally responsive closure, of a strut restrained at one end by said closure, and a valve, arranged on said strut at a distance back from said closure, for closing an opening in the distribution system in which the sprinkler is; there being beyond said 85 opening an auxiliary chamber and elements for operating a fire protective device by means of said strut, the said valve being adapted to close communication between the 90 distribution system and said chamber.

4. The combination, with a sprinkler head having a thermally responsive closure, of a strut restrained at one end by said closure, and a valve, arranged on said strut at a distance back from said closure, for closing an opening in the distribution system in which the sprinkler is; there being beyond said 95 opening an auxiliary chamber and elements for operating a fire protective device; said chamber including a diaphragm in which is 100 said opening closed by the valve and having fluid under pressure communicating with fire protective apparatus adapted to be released by release of said fluid.

5. The combination, with a sprinkler head having a thermally responsive closure, of a strut restrained at one end by said closure, and a valve, arranged on said strut at a distance back from said closure, for closing an 105 opening in the distribution system in which the sprinkler is; there being beyond said opening an auxiliary chamber and elements for operating a fire protective device, said chamber being separated from the distribution system by said valve, pressure in which 110 system seats said valve toward the auxiliary chamber; there being a stop limiting the movement of the strut toward said closure.

6. The combination, with a sprinkler head 120 having a thermally responsive closure, of a strut restrained at one end by said closure, and a valve, arranged on said strut at a distance back from said closure, for closing an opening in the distribution system in which the sprinkler is; there being beyond said 125 opening a connection to a fire protective device; said sprinkler head having a screw base whereby pressure may be applied by it through said strut to said valve to maintain 130

- it seated while ready for action and thus to keep the distribution system tight.
7. The combination with a sprinkler head having a thermally responsive closure of a strut pressing outward on said closure and standing in the discharge passage leading thereto while the closure continues; said strut being provided with means whereby it avoids obstructing said passage upon the opening of the closure; the whole being adapted in combination to form part of a connection with a fire protective device and to restrain the operation thereof until the said opening of the closure releases it.
- 15 8. The combination of a mechanically acting system for fire protection and a sprinkler system for fire protection with a single thermally operated device closing the sprinkler system and holding the mechanical system set ready for action; there being a mobile point of connection between the device and the mechanical system which may be in any of various positions and yet accommodate that position of said device in which it makes 25 tight closure of the sprinkler system.
9. The combination of a mechanically acting system for fire protection and a sprinkler system for fire protection with an automatic thermally controlled sprinkler head in 30 the sprinkler system; the automatic element of the sprinkler head being arranged to control also the mechanical system; the said systems being constructed and arranged with reference to each other so that there is a control element in the mechanically acting 35 system which may be set in any part of a certain zone and yet be ready for action to release its system, and the sprinkler head of the sprinkler system being arranged to set the 40 said element in some part of said zone when it is itself seated tightly.
10. The combination of a mechanically acting system for fire protection and a sprinkler system for fire protection with controlling 45 mechanism for both systems in which a single element closes the sprinkler system and holds the mechanical system in restraint; the restrained forces of the two systems being imposed upon the said element in substantial- 50 ly the same direction, with the said force of the mechanical system having a range of points of application permitting the said element to be set tightly with respect to the sprinkler system.
- 55 11. The combination of a mechanically acting system for fire protection and a sprinkler system for fire protection with controlling mechanism for both systems, comprising a thermally responsive sprinkler head on which 60 the restrained forces of both systems are imposed in substantially the same direction; the point of application of the force of the mechanical system being variable in the said direction to permit the sprinkler to be set 65 tightly with respect to the sprinkler system.

12. The combination with a sprinkler head structure and a closure cap therefor, of an extraneous protective device, a releasing member therefor associated with the closure cap and tending to move the same to its open 70 position and a thermally responsive control member holding the cap in its closing position.

13. The combination in a sprinkler head structure, of a closure cap therefor, external, 75 thermally released means for holding the cap in its closed position, and an interior valve member resiliently engaging the cap and tending to move the same to its open position, said valve member controlling an 80 inlet to the sprinkler head.

14. In an automatic fire protection system, the combination with a sprinkler discharge head and an extraneous protection device arranged for coincident operation, of 85 a closure cap for the head, a release member for said device comprising a loaded strut located within the head and tending to move the cap to its open position, and external, thermally released means for holding the cap 90 in its closed position.

Signed at Chicago, Illinois, this twenty-eighth day of March, 1921.
